UNITED STATES PATENT OFFICE.

JOHN B. HADAWAY, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY.

HEEL.

Application filed April 6, 1922. Serial No. 550,165.

This invention relates to heels and, more particularly, to rubber or other cushion heels.

In attaching rubber heels, or half heels, to the heel seat of a shoe or to a heel base, one of the ever present problems is to secure a joint between the rubber and the leather which will be tight and will remain so permanently. The points at which the tendency of the rubber heel to leave the base, to which it is attached, is the greatest are at and near the breast corners of the heel. Many attempts have been made to overcome the natural tendency toward a loose joint at these points but none has been unqualifiedly successful. The most common expedient which inventors have tried in attempting to overcome this difficulty has been to form the heel in some peculiar shape which, it was expected, would cause it to hug tightly to the base around the edge and at the corners. A great many freak shapes have thus been produced but all of those heels which attain any measurable degree of success in the accomplishment of the desired result are so distorted when in their normal, unstrained condition, that it is commercially impracticable, if not mechanically impossible, to attach them with heelng machines. Another difficulty is often encountered in the shoe factory in the process of trimming the base to which a rubber heel has been attached. The commercial machines used for this purpose utilize the edge of the rubber heel section as a guide to determine the size and shape to which the base is to be trimmed. Considerable pressure of the work against the cutter of the trimming machine is necessary when the cut is started, at one corner of the heel, and, when the rubber in this vicinity is free to yield, the cutter enters too deeply into the base with the result that, when the rubber section has again expanded to its normal condition, the rubber and base sections do not fit each other.

Some inventors have sought to overcome the difficulties above indicated by the insertion of a skeleton or other metallic plate in the heel, sometimes providing projections extending outwardly into the breast corners of the heel. These plates make it possible to secure a tight joint between the edge of the rubber heel and the base but none of these heels has ever been successful, partly because the plate, in a large measure, imparts rigid-

ity to the rubber heel and detracts greatly from its resiliency and flexibility, and partly because the shrinkage of the rubber compound in the curing process tends to cause it to separate from a rigid plate of any considerable size and to draw the nail holes in the rubber out of register with those in the plate.

It is the object of the present invention to produce a cushion heel which will be superior to those heretofore known, in that it may be easily attached by machine or otherwise, in the same manner as heels now in commercial use, while insuring a permanently tight joint between the heel and the base to which it is attached at the breast corners, even though no cement be employed in the attachment. With the attainment of this object in view, the invention contemplates the provision of a small, narrow plate or plates, preferably of resilient metal, in the breast portion only of the heel and, in the preferred form of the invention, extending well forward into the breast corners of the heel. In the specific embodiment of the invention herein illustrated two such small spring tensioning members or plates are provided, one on each side of the longitudinal median line of the heel, the two plates being substantially separated from each other and of such restricted size as not to affect the resiliency or flexibility of the heel as a whole to any detrimental degree nor to interfere with its natural shrinkage in the curing process. Each of these tensioning plates may be provided with one or two nail holes, thus permitting the plates to replace certain of the usual washers in the heel and insuring permanency of their location and action. Each plate preferably has at least one nail hole located in an intermediate portion of the plate and has a projection extending angularly from its body portion into a breast corner of the heel, the body portion lying close to the breast edge of the heel. Thus, when the intermediate portion of the plate is drawn down and placed under tension by an attaching nail the ends of the plate are permanently in a state of stress and have a permanent tendency to hold the breast corner of the heel and a portion of the breast edge of the heel tightly in contact with the shoe. The heel may advantageously be formed with a moderate concavity on its inner face, especially near the edges, and a

similar convexity on its tread face. As herein illustrated, the corner stiffening or tensioning plates are substantially flat when the heel is allowed to assume its natural shape, becoming somewhat curved when the heel is flattened under the attaching pressure and thereby producing a substantial amount of tension which causes the corners and breast edge of the rubber heel to press tightly against the base and permanently maintains a close joint.

While the attached drawings show a rubber half heel, it should be understood that the invention is equally applicable to whole heels and top lifts; and it should further be understood that wherever the term "rubber" is used to refer to the heel it is to be construed to cover any rubber or other composition suitable for making cushion or resilient heels.

Further features and advantages of the invention will be better understood from reading the following detailed description of one embodiment thereof, in connection with the accompanying drawings, in which

Fig. 1 is a view of the tread face of a rubber heel embodying the invention, a portion of the material being broken away to reveal the interior;

Fig. 2 is a cross section on the line 2—2 of Fig. 1;

Fig. 3 is a perspective view of one of the corner stiffening plates;

Fig. 4 is a view, largely diagrammatic, showing a shoe and heel in position ready for the driving of the attaching nails in a heel-ing machine; and

Fig. 5 is a sectional view on the same line as Fig. 2 showing the heel attached to a shoe.

Referring now to the drawings in detail, 10 indicates the heel which may be made of rubber or any of the usual compositions employed in making cushion heels. Holes 12, through which the attaching nails are to be driven, may be molded in the tread face of the heel, certain of these holes being surrounded by washers 14 and others left blank to permit the practice of the improved 45 method of attaching a rubber heel and a base at a single nailing, which is described and claimed in my copending application, Serial No. 487,814 filed July 25, 1921.

Embedded in the breast corners of the heel 50 are two separated, symmetrically arranged plates 16, arranged crosswise of the heel approximately parallel to its breast edge and having angularly disposed points 18 which project into the breast corners of the heel. 55 These plates may be made of any suitable material such, for example, as flexible spring steel and, as shown, are flat, although this is not essential. Each of the plates 16 is provided with two holes 20, of sufficient size to 60 permit the passage of the shank of a heel

nail while preventing the head from passing through. The holes 20 may advantageously be spaced to correspond to the spacing between the washer pins in the breast portion of the mold in which the rubber heel is formed, in order that the plates may be supported upon the pins in the same manner as washers while the heel is being made. As shown in Fig. 2, the tread face of the heel is convex around the edge at 22 and the inner 75 face is correspondingly concave, as shown at 24, when the heel is in its normal shape.

Fig. 5 shows the heel attached to a shoe 26; 28 indicating the heel seat portion of the shoe sole and 30 indicating a base section, such as is commonly employed with rubber half heels. When thus attached the heel is flattened out and secured by headed nails 32 which are clinched on the inside of the shoe. As an incident to the flattening out of the 85 heel the points 18 of the plates 16 are curved outwardly, as shown clearly in Fig. 5 and, in this condition exert a constant tension, tending to press the corners of the rubber heel tightly against the base. Although it 90 is not essential for the purposes of the invention that the attaching nails pass through the plates 16, I believe that the most effective and permanent result is secured by passing the nails through the plates, as illustrated. 95

Inasmuch as the location of the plates 16 is confined to the breast portion only of the heel where resiliency is of small importance, it is not essential that the plates be separate but, in the higher development of the invention, it is preferable that they be separate and independent in order to minimize any tendency toward rigidity in the heel.

A cushion heel having nail head engaging washers at certain nailing locations and 105 stiffening members of larger area and a shape different from that of the washers at other nailing locations is not claimed broadly herein but is claimed in my Patent No. 1,586,556, granted June 1, 1926 upon an application, Serial No. 607,077, filed December 15, 1922, as a continuation of the present application, as to all subject-matter which is common to both applications.

Having described the invention, what is 115 claimed as new and desired to be secured by Letters Patent is:—

1. A cushion heel having a pair of narrow, unconnected tensioning members arranged crosswise of the heel close to its breast edge, 120 each of said tensioning members having a heel material supporting end projecting into a breast corner of the heel at an angle to the body portion of said member, and being devoid of any projections extending toward 125 the rear of the heel.

2. A cushion heel having a pair of narrow, separated tensioning members the body portions of which lie approximately parallel to the breast edge of the heel, each of said 130

members having a projection shorter than the body portion extending angularly therefrom into a breast corner of the heel and being devoid of any projections extending toward the rear of the heel.

3. A cushion heel of normally concavo-convex cross section transversely, having embedded in the concavo-convex part a transversely disposed normally flat, flexible plate.

4. A cushion heel of normally concavo-convex cross section transversely, having em-

bedded in the concavo-convex part a transversely disposed normally flat, resilient plate.

5. A cushion heel having across its breast portion only a plurality of separate and independent stiffening plates, said plates projecting forwardly into the breast corners of the heel.

In testimony whereof I have signed my name to this specification.

JOHN B. HADAWAY.
